UNITED STATES PATENT OFFICE.

FRANK A. MILLS AND THOMAS A. MOSSOP, OF PHILADELPHIA, PA.

COMPENSATING PENDULUM.

SPECIFICATION forming part of Letters Patent No. 279,176, dated June 12, 1883.

Application filed June 8, 1882. (No model.)

To all whom it may concern:

Be it known that we, FRANK A. MILLS and THOMAS A. MOSSOP, citizens of the United States, residing at Philadelphia, in the county 5 of Philadelphia and State of Pennsylvania, have invented a new and useful Improvement in Compensating Pendulums, of which the following is a specification.

The nature of our invention will be understood by the following description and claims thereto appended.

In the accompanying drawings, which make a part of this specification, Figure 1 is a side elevation of our improved pendulum. Fig. 2 15 is a front elevation of the same. Fig. 3 is a bottom view with the ball G removed.

Like letters of reference in all the figures indicate the same parts.

The pendulum-rod is composed of two bars 20 of different degrees of expansion and contraction to compensate for the variations of temperature; but, instead of having the two bars separated and connected together by means of cross-bars, they are held flat together by means 25 of screws. The bars are of such form in their cross-section that when brought together they form a round, or hexagon, or octagon, or any other form of rod which may be desired. In the drawings they are half round and form a 30 round rod, the two flat sides being brought together.

The bar A is of steel, and the bar B of brass. They are held together to form a single rod by 35 means of screws a. The heads of the screws are countersunk in the brass bar and pass through the elongated holes in the bar, the steel bar being tapped to receive the threaded ends of the screws. The countersinks in the brass bar are enlarged to unite with the 40 enlargement of the holes in admitting such longitudinal movement of this bar over the steel bar as may be necessary during the expansion and contraction of the two bars. The lower end of the steel bar A has an elbow, c, to which is connected the horizontal 45 lever C by means of the fulcrum-pin d. The

brass bar B is forked, leaving the part e straight, and the part e' is turned in the manner represented, so as to bring its lower end far enough from the part e for combining the horizontal 50 screw-rod D with the said parts e and e'.

E is a disk on the screw-rod D, and is adjustable thereon by means of the screw-thread connection. The peripheral edge of the disk bears upon the upper edge of the lever C, 55 which has a concave longitudinal groove, f, so as to form two bearing-edges to come in contact with the disk to keep the latter steady.

G is the ball, having a screw-rod, h, provided with hooks i i, which are connected with the 60 pin j of the lever C in line with the rod A B, whereby to bring the vertical strain upon said rod at its central line.

The object of having the disk E adjustable on the rod D is to admit of making the distance between its bearing on the lever C and the fulcrum-pin d variable with the distance between said pin and pin j, upon which the ball G is hung, in adaptation to the difference in the degrees of expansion and contraction of 70 the bars A and B.

It will readily be seen that by hanging the ball in line with the rod a much easier movement is given to the oscillations, and that the compactness of the rod gives simplicity thereto 75 and very much improves its appearance, and likewise cheapens the construction of the pendulum.

We claim as our invention—

1. In a leverage compensating pendulum, 80 the combination of the ball G, having a rod, h, provided with hooks i i, with the lever C, having a pin, j, arranged in the central plane of the rod A B, substantially in the manner and for the purpose set forth. 85

2. The rod of a compensating pendulum, having bars A B, of unequal expansion and contraction, and the bar A having screws a, and the bar B slotted, substantially in the manner and for the purpose set forth. 90

3. The combination of the screw-rod D, having an adjustable disk, E, with the bar B, hav-

ing legs *e* and *e'*, the ball *G*, having a rod, *h*, provided with hooks *i i*, and the lever *C*, having a fulerum-pin, *d*, and pin *j*, substantially in the manner and for the purpose set forth.

5. 4. In a compensating pendulum having its rod composed of bars *A* and *B*, the combination of its lever *C*, having a fulerum-pin, *d*, with the bar *A*, having an elbow, *e*, provided with the fulerum-pin *d*, the elbow and bar being in a single piece, substantially as described.

5. In a rod of a compensating pendulum composed of bars *A* and *B*, the bar *B* and its

legs *e* and *e'*, made in a single piece, substantially as described.
